Patented Feb. 1, 1966

203,592

MAGNETIC DISC TRANSPORT UNIT

Marvin A. Southcott, San Francisco, and Robert W. Bornschlegel, Millbrae, Calif., assignors to Ampex Corporation, Redwood City, Calif., a corporation of California

Filed Apr. 3, 1964, Ser. No. 79,336

Term of patent 14 years

(Cl. D26—5)

Des. 203,592

PAGE 2

FIGURE 1 is a front and right side perspective view of a magnetic disc transport unit, showing our new design;

FIGURE 2 is a rear and left side perspective view; and

FIGURE 3 is a front elevational view.

We claim:

The ornamental design for a magnetic disc transport unit, substantially as shown.
